UNITED STATES PATENT OFFICE.

WARREN K. BLODGETT, OF CAMBRIDGE, MASSACHUSETTS.

HASP-LOCK.

No. 855,087.

Specification of Letters Patent.

Patented May 28, 1907.

Application filed August 5, 1905. Serial No. 272,835.

To all whom it may concern:

Be it known that I, WARREN K. BLODGETT, of Cambridge, in the county of Middlesex and State of Massachusetts, have invented 5 certain new and useful Improvements in Hasp-Locks, of which the following is a specification.

This invention relates to hasp-locks for use in securing transportation companies 10 against the unauthorized opening of doors of freight-cars and other receptacles; and particularly to that class of hasp-locks employing a hasp retaining member, a lock-casing, and a seal-strip of resilient material such as 15 sheet metal, the hasp-retaining member and lock-casing having each a passage for the seal-strip which extends through both and unites them, when properly assembled, and the lock-casing and seal-strip being provided 20 with locking members which are caused to automatically interlock by the operation of inserting the strip into the lock-casing. It is to be understood, however, that I do not limit myself to the particular use referred to 25 in connection with doors, since the parts may be employed to lock or secure other relatively movable structures.

One of the objects of my invention is to provide a hasp-lock, of the character mentioned, 30 so constructed or arranged that access to the seal-strip at or adjacent to the point where the strip joins the two members will be prevented, so that it would be impossible for an unauthorized person to break or 35 cut the seal-strip at this point and then conceal the tampering by soldering the two parts of the severed strip together.

Another object is to provide a construction in which the mouth of the seal-lock is 40 clutched in position to relieve the neck of the seal from undue strain.

Another object of the invention is to provide a structure in which the hasp-retaining member and the lock-casing, each having a 45 passage for a seal-strip, can readily be brought into alignment and contact for the proper insertion of the seal-strip, but cannot be improperly connected so that a seal-strip can be inserted in an incorrect way.

50 Another object of the invention is to combine the hasp-retaining and locking members as inseparable parts of a single structure which will be interchangeable on all car doors, whether rights or lefts; making unnecessary the construction or installation of

the lock-casings as rights and lefts; which will allow the seal-strip to be always inserted (whether on right or left hand doors) with the right hand if desired; and which will make unnecessary the printing of the 60 seal-strip on both sides in order to accommodate it to opposite positions on different car-doors.

To these ends the invention consists in the construction and combination of parts 65 substantially as hereinafter described and claimed.

Of the accompanying drawings:—Figure 1 represents a front elevation of a door and casing with devices including one embodiment of my invention attached thereto, the parts being represented in unlocked position. Fig. 2 represents a side elevation from the left of Fig. 1, omitting the hasp and its supporting member. Fig. 3 is a view similar to 75 Fig. 1, with the parts in locked position. Fig. 4 represents a section on line 4—4 of Fig. 3. Fig. 5 represents a section on line 5—5 of Fig. 3. Figs. 6, 7, 9, 10 and 12 are views similar to Fig. 3, but illustrating modified arrangements or different constructions 80 of the device. In Figs. 9, 10 and 12, the drawing of the hasp has, to economize space, been omitted. Fig. 8 represents a side elevation of the hasp-retaining and locking 85 member shown in Fig. 7. Fig. 11 represents a section on line 11—11 of Figs. 9 and 10. Fig. 13 represents a section on line 13—13 of Fig. 12. Fig. 14 represents the bolt or pin shown in Fig. 12, detached from the lock- 90 casing.

The same reference characters indicate the same or similar parts throughout the several views.

Referring first to Figs. 1 to 5, inclusive, 95 portions of a door and a casing therefor are indicated respectively at 20 and 21. These parts, 20 and 21, however, may be understood to represent other relatively movable parts which are to be locked together. For 100 convenience of description, however, I shall hereafter refer to them as the door and casing respectively.

The hasp or shackle 22, which may be of an ordinary kind having an eye-hole or slot 23, 105 is connected to the door 20 by a suitable eye or staple 24, so that said hasp or shackle may be conveniently shifted from the position shown in Fig. 1 to that indicated in Fig. 3. It is obvious that on left-hand doors, the 110

hasp will be on the left side of the casing, and on right-hand doors on the right-hand side of the casing.

Suitably secured to the casing 21 is a base-plate 25, having upper and lower eye-lugs 26 and 27 respectively, the eyes of said lugs being adapted to carry the bolt or hasp-retaining member 28. As best shown in Fig. 4, the eye of the upper lug 26 is larger than the eye 10 of the lower lug 27.

The hasp 22 is adapted to be engaged with the upper lug 26 by being slipped thereover to the position shown in Figs. 3 and 4, said upper lug 26 being preferably provided with 15 a notch or recess 39 in its upper surface near the base-plate, so that the hasp when swung to will be positively held in the position where it will not interfere with the movements of the bolt or hasp-retaining member 20 28 and will leave the door fastened even when unlocked.

* The bolt 28 is formed with a head 29 sufficiently large to prevent its passage through the eye of the lower lug 27, said head, however, being adapted to freely enter the eye of the upper lug 26. Said head 29 prevents the bolt from dropping entirely away from the lower lug, as shown in Fig. 2. The bolt, 28, is limited to a vertical movement and 30 prevented from any sidewise or turning movement, preferably by making the eyes of the lugs 26 and 27, oval in shape, and that portion of the bolt which plays through them, a similar oval, one diameter being sufficiently 35 larger than the other to prevent turning the bolt in the eyes. The same result may be accomplished in other ways, as by making the bolt and the eyes rectangular or otherwise irregular in form, or by placing stops on 40 the surface of the lug which engage suitable projections on the bolt. One side of the bolt 28 is formed with a recess 30, of such size and shape as will admit the entrance of the end of the lock-casing 34, from the bottom 45 of which recess slot 31 extends through to the opposite side of the bolt, so as to form a passage for the seal-strip. The bolt 28 is formed with a hole 32 from which a link 33 depends loosely, absolutely preventing the removal 50 of the bolt upward from the lugs, and said link being pivotally connected, also, with the lock-casing 34 makes both bolt and lock-casing permanent or inseparable parts of the whole fixture. The mutual adjustment of 55 said bolt-hole, link, and lock-casing is such as to enable the lock-casing to move only (except for a little necessary play) in the circumference of a circle whose radius is just sufficient to let the entrance tip or mouth of 60 the lock-casing reach into the recess 30 against the seal-slot 31, and in combination with the immobility of the bolt horizontally, to prevent the entrance tip of the lock-casing from being brought up against the seal-slot 65 on its back side or in any other incorrect

way; and also to prevent the wrong or exit end of the lock-casing from being brought up to the recess 30 in locking position under any circumstances. In order, further, to prevent the wrong or exit end of the lock-casing from being carried to a position on the back of the bolt where the lock might be imperfectly sealed by a reverse motion, the link may be wholly prevented from swinging on the wrong side of the bolt, if desired, by a 75 suitable enlargement or stop on the bolt; but I prefer to construct the lock-casing itself in such a way as to prevent the wrong end from reaching the seal-slot by providing a toe 38 projecting from the rear end of the 80 casing, or to so construct the lock-casing internally that a seal-strip cannot be passed through it which enters at its exit end.

It is not necessary to illustrate or describe the details of the internal structure of the 85 lock mechanism embraced in the casing 34, since devices are well known in which a casing and a resilient seal-strip are provided with locking members which automatically interengage when the strip is moved in one 90 direction into or through the casing, but which prevent the strip from being removed from the casing in the return direction. I have represented the passage for such strip as at 35 and the strip itself at 36, the said 95 strip having a widened portion or head 37. As will be readily understood, the strip 36 is designed to be introduced through the slot 31 of the bolt and then into and through the passage 35 in the lock-casing 34 until the 100 head 37 reaches the outer surface of the bolt 28, as indicated in Fig. 3. At this point the interengaging members (not shown) of the lock and seal-strip will hold the seal-strip so that it cannot be withdrawn, thereby necessitating the breaking or tearing of the head 37 to enable the bolt to be withdrawn from its hasp-retaining position. Of course, when the parts are to be changed from the position shown in Fig. 1 to that shown in Fig. 3, the 105 hasp or shackle 22 is first engaged with the upper lug 26, as hereinbefore described, the bolt 28 is moved upward to the position shown in Fig. 4 and then the lock-casing 34 is swung around so that its tip enters the 110 recess 30 in the bolt. This results in bringing the passage 35 of the lock into alignment with the slot 31 of the bolt, so that the seal-strip may be readily inserted as described. 115

In Fig. 6 I represent practically the same 120 details of construction as in Figs. 1 to 5, but with the plate 25 and its parts reversed, so that the bolt will be moved downward instead of upward when passing to position to cross the hasp or shackle.

It is obvious that in Figs. 1 to 6 the link instead of being attached to the bolt, might, if desired, be attached to the baseplate itself, by forming a small extension or ear projected suitably downward or outward, as in 125 130

Figs. 7, 9, 10 and 12, but this would require an extra fastening to prevent the withdrawal of the bolt from the lugs. It is also obvious that the link might be separated 5 from the structure and attached to the casing immediately below or above the structure, in the same relative position as when attached as herein described; but this has the additional disadvantage of making the lock-casing a separate piece, with an extra cost of 10 attachment, more easily capable of loss, and requiring skill and knowledge in suitably attaching it to the car-casing and adjusting it to the other members.

15 In Figs. 7 and 8, the bolt or pin is eliminated; the baseplate is formed with a vertical lug 60, which is the hasp-retaining member, and which has at a suitable point in one side, a recess 62 of such size and shape 20 as will admit the entrance of the end of the lock-casing 34, with a slot or passage 61 extending through from the bottom of the recess to the opposite side of the lug, to form a passage for the seal-strip through said slot and 25 into the lock-casing, when the latter is inserted in the recess. In this form of lock, the hasp or shackle 22 is, of course, formed with a vertical slot 63 to enable it to pass over the vertical lug 60. The baseplate is 30 extended downward and outward in an ear 64 to a point where the connecting link 65 may swing pivotally, carrying the mouth of the lock-casing to the recess in substantially the same manner as described in connection 35 with the forms previously illustrated.

In Figs. 9, 10 and 11 the construction and operation are quite similar to that in Figs. 1 to 6, but the bolt or hasp-retaining member is composed of a strip of sheet metal 40 bent 40 at one end to form a handle 41, by which it may be moved upward or downward but is prevented from being removed from the fixture, and provided with an offset portion forming a recess 44, said offset portion being 45 formed with a slot 45, as shown in Fig. 11. The baseplate 25 is formed with a small extension or ear 46, projected downward or sidewise and outward, to which is pivotally connected a link 33, the lock-casing being 50 pivoted to the other end of said link. It is obvious that, if desired, the link may be connected to the handle or head of the bolt as in Figs. 1 to 6. In this form the end of the lock-casing is formed with an extension or 55 yoke 47 forming a recess which will receive the offset portion 44 of the bolt. The passage 35 in the lock-casing will be in alignment with the passage 45 of the offset or recessed portion 44 of the bolt, when the parts 60 are interengaged as shown in Figs. 9, 10 and 11, so that the seal-strip may extend through both to join the two members. In this form it may be said that each member has a recess which receives a portion of the other member, since the offset 44 forms a recess on one

side and the yoke 47 of the lock-casing forms a recess which receives a part of the bolt 40.

In Figs. 12, 13 and 14, I have shown the bolt or pin 72 of sheet metal, bent at its head 41 to prevent its removal downward, and 70 twisted below its center to prevent its removal upward through the vertical slot of the upper lug; and I have shown the lock-casing 34 formed with an extension 70 having a vertical opening or recess that is substantially rectangular in cross-section. The outer wall of said recess is formed with a slot 71 in alignment with the seal-strip-passage 35 within the casing. The bolt is adapted to 75 rest and be guided in a vertical slot formed in the lug 26 and an eye in the lug 27 of the base-plate. Said bolt 72 is formed with a slot or passage 74 which, when the parts are 80 in position to receive the seal-strip, will be in alignment with the passages 35 and 71 of the lock. The extension 70, having the vertical recess, has the lower opening partly closed and the portion of the bolt 72 which projects through said lower opening is narrower than the part above, thus making an enlargement 90 or shoulder 75 serving as a protection for the lower orifice, and preventing the insertion of a file or saw from below, for the purpose of severing the seal-strip; a second and similar enlargement 76 is made on the bolt 72 where 95 it emerges from the upper orifice of the recess, and for a similar purpose, as shown in Fig. 14. It is obvious that the vertical opening or recess instead of being rectangular, may adapt itself to any form of bolt desired, 100 whether sheet metal or iron casting, circular, oval or irregular.

It will be seen that I have provided a structure in which the bolt forms a hasp-retaining member, and the casting 34 and the parts 105 contained therein form a locking member for said hasp-retaining member; these two members having passages for the seal-strip which extends through both, and the two slots or 110 pasages being in alignment when brought to the position which they must occupy for the insertion of the strip; the bolt or hasp-retaining member having a recess which receives the tip portion of the other, and thus prevents access to the strip at or adjacent to the 115 point where the strip joins the two members, and also, by clutching the top and bottom and two sides of the lock-casing, when in position, in combination with the link, assists in preventing the swing of, and in carrying 120 the weight of, the lock-casing, and thus in taking a portion of the strain off the neck of the seal-strip. It will also be seen that I have provided a structure, with the help of 125 the link, in which the hasp-retaining member and the locking member are made as inseparable parts of one hasp-retaining and locking fixture, which fixture is capable of receiving the hasp either from the right-hand or the left, and in which the link allows the lock- 130

casing to hang, balanced, when not in use, with sufficient movement from the motion of the car to free it from sand or snow, and to yield without injury if struck; and also in which the link assists in carrying the weight of the lock-casing when locked in position. It will further be seen that I have lessened the danger (found in the ordinary method of hanging the lock-casing and bolt each by a separate chain, the lock from the door and the bolt from the casing) of the separation of one or the other from the structure; I have avoided the changes necessary in making the lock casings rights and lefts on account of right-hand and left-hand doors; I have avoided the necessity of sealing one half the locks with the left-hand; and I have avoided the necessity of printing the seal-strip on both sides in order to enable it to be read either in a right-hand or left-hand lock.

I claim:

1. A hasp-lock comprising a hasp-retaining member having a transverse seal-strip passage, and a movable locking member for said hasp-retaining member, said locking member having a seal-strip passage extending from end to end thereof, whereby a seal-strip will hold the locking member in end-wise position relatively to the hasp-retaining member.
2. A hasp lock comprising a hasp-retaining member and a movable locking member for said hasp-retaining member, said members having each a passage for a seal-strip to extend through both, one of said members having a recess to receive a portion of the other member for the purpose of preventing access to the seal-strip at or adjacent to the point where the seal-strip joins the two members, and by clutching the mouth of the locking member in position, relieving the neck of the seal-strip from undue strain.
3. A hasp lock comprising a hasp-retaining member and a movable locking member

for said hasp-retaining member, said members having each a slot or passage for a seal-strip to extend through both, the passage through the locking member extending longitudinally thereof and one of said members having a recess to receive a portion of the other member, the passages of the two members being in alinement when a portion of one member is in the recess of the other member.

4. The combination with a hasp, of a retaining member therefor and a locking member for the retaining member, said members being formed with passages for a seal-strip, the passage through the locking member extending longitudinally thereof, the retaining member having a recess to receive the tip or end of the other member when the two members are assembled with their passages in alinement.

5. A hasp lock comprising a hasp-retaining member and a movable locking member for said hasp-retaining member, each of said members having a passage for a seal-strip to extend through both, the passage through the locking member extending longitudinally thereof and said members having means to prevent their being incorrectly assembled.

6. A hasp lock comprising a hasp-retaining member and a movable locking member for said hasp-retaining member, each of said members having a passage for a seal-strip to extend through both, the passage through the locking member extending longitudinally thereof and said members being formed to permit the hasp to be swung to and engaged by the hasp-retaining member from the right side or from the left side of the latter.

In testimony whereof I have affixed my signature, in presence of two witnesses.

WARREN K. BLODGETT.
